ABSTRACT

A pump of the eccentric rotor offset sliding blade type has the blade slots of such depth, in relation to the length of blades approaching the fully worn condition, that upon re-starting after stoppage worn blades remain retracted in their slots and cannot escape to cause jamming and damage to the pump.

ROTARY PUMPS

This invention concerns improvements in rotary pumps of the eccentric rotor, sliding blade type. One kind of pump of this type has the blade slots tangential to a circle concentric with the rotor axis; this kind of pump is known as the offset blade type.

Offset blade pumps are very reliable in use, but, in common with other types of sliding blade pumps, they are liable to serious damage and jamming if a blade escapes from its slot when it is foreshortened beyond a certain degree by wear at the tip.

It is an object of the invention to obviate the possibility of blade escape despite maximum allowable or excessive blade tip wear in intermittently operated pumps of this kind.

According to the invention we provide an intermittently operated eccentric rotor offset sliding blade type pump having blade slots whose depth is chosen in relation to fully worn blade length such that the centre of gravity of a fully retracted worn blade lies behind the radius of the rotor intersecting its guide slot at right angles.

The expression "behind" used in the above definition signifies "displaced angularly contrary to the direction of pump rotation", as will be understood by those versed in the art.

Blades become fully retracted in their slots when the pump rotor is slowed down and stopped and are thrown out by centrifugal force to contact the inner surface of the stator upon re-starting, so long as their centres of gravity lie ahead of the aforementioned radii. However, if their centres of gravity lie behind these radii, i.e. towards the slot bases, centrifugal force tends to keep them retracted.

Blade slots of pumps in accordance with the invention are abnormally deep, and experience shows that no more than three can be provided in a small rotor without fear of introducing weakness where the base of

one slot approaches the side of an adjacent slot. However, in large pumps it will almost certainly be found possible to accommodate several additional slots.

In the ordinary course of events, it is ensured by 5 pump designers that blade retraction will not be maintained, so that a pump will operate effectively throughout the period of blade life. In contra-distinction a pump according to the present invention will "fail safe". That is to say, pump efficiency will be so obviously diminished that the requirement for blade replacement will be made evident before a damaging situation can arise.

The principle of the invention is illustrated in the accompanying diagrammatic drawing, which shows a rotor A driven by a shaft C in a stator casing B.

A fully worn blade D is shown in its extended position in contact with the stator wall. About half its length extends out of its guide slots and it can operate safely in this condition. The blade, referenced D1, is also shown in its fully retracted position, which it assumes when the rotor is stopped, and it can be seen that its centre of gravity X lies behind the radius R from the rotor axis which intersects the guide slots at right angles.

When the rotor is started, the blade will remain in the 25 retracted position and loss of efficiency will indicate the necessity for blade replacement.

The principle of the invention is certainly applicable to dry pumps, but it may be that oil viscosity could prevent full blade retraction in the case of certain lubricated pumps. Experiments in this connection are still 30 being carried out.

What I claimed is:

1. An intermittently operated eccentric rotor offset 35 sliding blade pump wherein guide slots for the blades are of such depth that the centre of gravity of a fully retracted blade when worn to the maximum allowable extent lies behind the radius of the rotor which intersects its guide slot at right angles.
